UNITED STATES PATENT OFFICE.

JAMES W. BREESE AND OSCAR L. HUPP, OF INDIANAPOLIS, INDIANA.

ADJUSTABLE SECTIONAL RAILROAD-CROSSING.

1,102,235.

Specification of Letters Patent.

Patented July 7, 1914.

Application filed April 23, 1914, Serial No. 833,923.

To all whom it may concern:

Be it known that we, JAMES W. BREESE and OSCAR L. HUPP, citizens of the United States, residing at Indianapolis, in the county 5 of Marion and State of Indiana, have invented certain new and useful Improvements in Adjustable Sectional Railroad Crossings, of which the following is a specification.

- 10 The object of this invention is to provide smooth and durable wearing surfaces for streets, roads and sidewalks at places where they intersect railways for steam and electric cars.
- 15 A further object is to provide such crossings in a plurality of independently removable sections whereby any one or more of said sections may be removed for repairs or for the substitution of a new section without 20 disturbing the other sections.

We accomplish the above and other objects by the mechanism illustrated in the accompanying drawing, in which—

Figure 1 is a top plan view of a railroad crossing embodying our invention, and shows the use of a double row of sections extending transversely of the railroad track. Fig. 2 is a vertical cross section on the line 2—2 of Fig. 1. Fig. 3 is a cross section of one of 30 the sections showing the manner in which the transverse partitions are secured, and Fig. 4 is a like cross section near the inner end of our removable road section. Figs. 3 and 4 are on a larger scale than the other figures 35 of the drawing.

Like characters of reference indicate like parts throughout the several views of the drawing.

The railroad rails 5, and the cross-ties 6 are of the usual size, shape and material, and as is customary, the ties are set approximately eighteen inches apart on centers. The drawing shown in Fig. 1 represents a wagon road crossing for country roads, but 45 the device is equally applicable to crossings for city streets, sidewalks, and the like.

Instead of the heavy wooden planks ordinarily used at the crossings under discussion, which warp out of shape and become loose 50 and deteriorate rapidly by decay, we substitute a plurality of our improved crossing sections, the number of which will depend upon the width of the roadway crossing the railroad track, and also upon the size of 55 the sections themselves which may be varied

in dimensions to suit the conditions and requirements.

Our improved crossing section comprises a metal box, preferably hardened steel, having sides 7, ends 8, and bottom 9 which are preferably integral portions of the box. It also comprises a plurality of transverse walls or partitions 10, preferably formed out of cast iron, rendered malleable by annealing, and having integral end rivets 11, which are inserted in suitable openings in the sides 7 of the box, and their ends secured by being expanded in countersinks by hammering, as shown in Fig. 3, so as not to form any projections beyond the sides 7 which might interfere with the close assembly of the sections in forming a crossing. The malleable partitions are bent to permit assembly in the box and are straightened therein, causing their integral rivets to enter the openings in the sides of the box formed thereto to receive them. The section is thus divided into smaller compartments or panels by means of the partitions 10, and these panels are filled with any suitable road material. We have, 20 here shown them to be filled with paving bricks 12, and the depth of the box is such as to cause the upper edges of the bricks, laid in edgewise, to be even with the tops of the partitions 10. The purpose in making the, 25 partitions 10 out of iron instead of steel, like the sides of the box, is to cause the partitions and bricks to wear down uniformly, and also faster than the sides and ends of the hardened steel box, thereby causing the latter to project sufficiently above the partitions and bricks to afford a secure footing for the feet of draft animals against said projecting hardened steel members. The smaller compartments may be filled with wooden 30 blocks, asphalt, or any other usual and suitable road surfacing material instead of bricks, if desired. Suitable holes will be formed through the bottom 9 of the crossing sections for the passage of long spikes 13, the lower ends of which are driven securely 35 down into the cross-ties 6. Notches are formed in the sides 7 of the sections to receive the spike heads and to permit them to be driven down below the top edges of said 40 sides 7 with the heads resting in said notches on the sides in a manner as shown in Fig. 4, to fasten the sections securely to the ties. The partitions 10 will preferably be placed 45 so as to come directly over the ties, and the 50

55

length of the sections will be such as to cause their ends to terminate directly above the ties in like manner; and the spike holes will be so located as to cause the spikes driven 5 through them to enter a corresponding one of the underlying wooden ties 6. The outer ends of the outer sections are provided with flanges 14, resting upon the ties, which are secured to the ties by spikes in the usual 10 manner in which the rails 5 are spiked.

While we have only shown two rows of sections, it is obvious that only one row or more than two rows may be used, as circumstances may require, and for the ends 15 of the inner sections and for the inner ends of the outer sections the flanges 14 will be omitted in order to permit the adjacent ends of the sections to be brought into close contact with each other, and in such cases the 20 inner ends of the sections will be secured by a pair of spikes, one at each corner of the section, as shown.

Guard-rails 15 will be introduced between the rails 5 and the crossing sections between 25 the rails, and the inner sides of the crossing sections located along the outside of the track will be thickened to contact with the web of the rail and to fill in the space under the head of the rail, as shown at 16 30 in Fig. 2.

While we have described our invention with more or less minuteness as regards details of construction and arrangement and as being embodied in certain precise forms, 35 we do not desire to be limited thereto unduly or any more than is pointed out in the claims. On the contrary, we contemplate all proper changes in form, construction, and arrangement, the omission of immaterial elements, and the substitution of equivalents, as circumstances may suggest or necessity render expedient.

We claim:

1. In a crossing for railways, a plurality 45 of separately removable boxes each having

metal sides and ends, partitions of softer material dividing the box into compartments, and paving material filling all of said compartments.

2. The combination with the rails and 50 cross-ties of a railway, of a plurality of separately removable metal boxes, a filling 55 of paving material within each of said boxes, and removable means for securing each box to said cross-ties.

3. The combination with the rails and 60 cross-ties of a railway, of an elongated metal box, partitions dividing the box into smaller compartments, paving material within and filling each of said compartments, and 65 means for removably securing the box to the cross-ties.

4. The combination with the rails and 70 cross-ties of a railway, of a plurality of elongated metal boxes assembled together 75 to form a roadway across the railway, partitions dividing each box into a plurality of smaller compartments, paving material within and filling each compartment, and spikes on the inside of said boxes passing through the bottoms of the boxes into the cross-ties, said spikes having heads overlapping the walls of the boxes.

5. The combination with the rails and 75 cross-ties of a railway, of a box having hardened steel side walls, softer metal partitions dividing the box into a plurality of smaller compartments, a filling of paving material within each of said compartments, and removable means for securing the box 80 to said cross-ties.

In witness whereof, we have hereunto set our hands and seals at Indianapolis, Indiana, this 13th day of April, A. D. one thousand nine hundred and fourteen.

JAMES W. BREES. [L. S.]
OSCAR L. HUPP. [L. S.]
